DESIGN FOR A RECEPTACLE FOR CIGARETTES AND OTHER ARTICLES

William J. Reilly, Taunton, Mass.

Application January 4, 1946, Serial No. 125,282

Term of patent 14 years

(CL. D85—2)

To all whom it may concern:

Be it known that I, William J. Reilly, a citizen of the United States, residing at Taunton, State of Massachusetts, have invented a new, original, and ornamental Design for a Receptacle for Cigarettes and Other Articles, of which the following is a specification, reference being had to the accompanying drawing, forming a part thereof.

In the accompanying drawing:

Figure 2 is a front elevational view of the same; Figure 3 is a side elevational view of the same. Various areas have contrasting appearance as indicated by stippling, hatching and solid.

In the specific embodiment of the design illustrated the sides of the device not shown but opposite the sides shown are substantially like the sides shown, respectively.

I claim:

The ornamental design for a receptacle for cigarettes and other articles, substantially as shown and described.

WILLIAM J. REILLY.
